UNITED STATES PATENT OFFICE.

JOHN M. HOWARTH, OF WAUSAU, WISCONSIN, ASSIGNOR OF ONE-FOURTH TO FRANK C. DANIELS, OF WAUSAU, WISCONSIN.

LANDING-CHAIR FOR ELEVATORS.

1,152,318.

Specification of Letters Patent. Patented Aug. 31, 1915.

Application filed July 17, 1914. Serial No. 851,601.

To all whom it may concern:

Be it known that I, JOHN M. HOWARTH, a citizen of the United States, residing at Wausau, in the county of Marathon and 5 State of Wisconsin, have invented certain new and useful Improvements in Landing-Chairs for Elevators; and I do hereby declare the following to be a full, clear, and exact description of the invention, such as 10 will enable others skilled in the art to which it appertains to make and use the same.

The present invention relates to landing chairs for elevators, and has for an object 15 to provide an improved landing chair for securing the elevator platform against accidental displacement when at rest at a landing.

It is an object of the present invention to 20 provide an improved landing chair for elevator platforms which will insure the platform being brought to rest in precise alignment, so as to thereby form a smooth joint between the platform and landing for the passage thereover of trucks, carriages or 25 other vehicles employed in the transportation of merchandise and the like.

It is a further object of the present invention to provide improvements in landing chairs for elevators which will form a stop 30 upon which the elevator operator may bring the platform to rest without having to exercise any undue care in endeavoring to bring the platform to a stop precisely level with the landing.

With these and other objects in view the 35 invention consists in the novel details of construction and combinations of parts more fully hereinafter disclosed and particularly pointed out in the claims.

In the accompanying drawings forming a 40 part of this application, and in which similar reference symbols indicate corresponding parts in the several views: Figure 1 is an elevational view of an elevator illustrating coöperating landing latches constructed in accordance with the present invention. Fig. 2 is a top plan view of an elevator platform and coöperating latch actuating mechanism, with the latches removed; and

Fig. 3 is a bottom plan view of one of the 50 latches constructed in accordance with the present invention.

Referring more particularly to the drawing, 1 designates a piston of the usual steam hydraulic or other suitable type of elevator, 55 and supporting a platform 2 in the usual manner. The platform 2 is operable through the piston 1, by means of the cable 3 connected to the valve lever 4, and operated in a manner as will be understood.

The valve lever 4 is connected by a rod 5 to an arm 6 mounted on one of a pair of rock shafts 7, journaled in brackets 8 secured to the building structure. The rock shaft 7 to which the arm 6 is connected is provided with a stub arm 9 depending therefrom, the same being connected by a link 10 to an upstanding arm 11 on the companion rock shaft 7. It will be understood by the arrangement above described that, upon actuation of the valve lever 4, through the cable 3, to operate the elevator, the rod 5, through the instrumentality of the arm 6, will actuate the associated rock shaft 7, from which latter a similar movement will 75 be communicated to the companion shaft 7 through the stub arms and connecting link 10.

Each rock shaft 7 is provided with a plurality of strikers 12, projecting substantially horizontally from the shafts and arranged to engage the lower arcuate ends 13 of bent levers 14, fulcrumed each in a pair of depending ears 15 projecting from casings 16 bolted to the underside of the landings, as shown. The bent levers 14 are 85 formed at their upper ends with spherical heads 17, arranged to occupy sockets 18 produced in latches 19 mounted for reciprocating movement in casings 16. The casings 16 are further provided in the bottom 90 walls thereof with elongated slots 20, for permitting of the oscillating movement of the bent levers 14 sufficient to move the latches 19 into and out of the casings, as will be hereinafter more particularly referred to. The latches 19 are connected at their rear ends with rods 21, arranged to slide in bearings 22 dependent from the

underside of the landings. The rods 21 form, with the latches 19, shoulders 23, between which and the bearings 22 are confined coil springs 24, the same encircling the rods 21.

5 The latches 19 are arranged to be normally projected into the elevator shaft beyond the landing and in the path of the elevator platform. In this position the upper outer edges of the latches are preferably 10 slightly inclined, as indicated at 25, to engage correspondingly inclined surfaces 26 on longitudinal flange 27 formed at each edge of the elevator platform. The elevator platform 2 is provided with recesses 28 15 provided with inclined rear walls 29, arranged in alignment with the several latches 19, and during upward traverse of the elevator platform the inclined walls 29 are adapted to encounter the beveled undersides 20 30 of the latch ends to force the same inwardly against the action of the coil springs 24 and permit the passage of the elevator.

In practice, assuming the elevator platform 2 to be at rest, as illustrated in Fig. 1, 25 in order to descend the operator pulls upon the cable 3, in the usual manner, to move the valve lever 4, which simultaneously draws down upon the rod 5 and connecting arm 6, and thereby causes actuation of the 30 rock shafts 7. Such action moves the strikers 12 to engage the arcuate ends 13 of the bent levers 14, and oscillate the latter about their fulcrums to retract the latches 19 within the casings 16 and out of engagement with the flange 27 on the platform 2, 35 so as to permit the same to descend in the usual manner. After the passage of the platform 2, the latches 19, inasmuch as permitted by the relative positions of the strikers 12 and levers 14, will be projected again 40 into normal position under the influence of the springs 24.

During ascent the inclined walls 29 of the recesses 28 will encounter the beveled portions 30 of the several latches 19, and thereby move the same inwardly and permit the passage of the platform.

It is to be understood that while I have illustrated the mechanism for a single landing, the same may be provided for any number of landings and operate from the valve lever 4 by mechanism similar to that herein shown and described.

It is obvious that those skilled in the art 55 may vary the details of construction and arrangement of parts without departing from the spirit of my invention, and therefore I do not wish to be limited to such features except as may be required by the claims.

60 I claim:

1. The combination with an elevator and operating means therefor, of latches mounted on the landing and arranged to project into the elevator shaft and form a support

for the platform, means for normally holding said latches in projected position, and means independent of said latch projecting means for retracting the latches out of the path of the elevator platform and including rock shafts connected to be actuated from the elevator operating means, and connections arranged between said rock shafts and latches for engaging and operating to retract the latter against the influence of said first-named means during descent of the elevator platform, substantially as described. 65 70 75

2. The combination of an elevator and operating means therefor, of latches mounted on the landing and arranged to project into the elevator shaft and form a support for the platform, levers associated with said latches, rock shafts, connections for actuating said rock shafts from the elevator operating means, and means on said rock shafts for engaging and operating said levers to retract said latches, substantially as described. 80 85

3. The combination of an elevator and operating means therefor, of latches mounted on the landing and arranged to project into the elevator shaft and form a support for the platform, spring means for normally holding said latches in projected position, rock shafts, connections between said rock shafts and the elevator operating means, and means arranged between said rock shafts and latches for retracting the latter during descent of the elevator platform, substantially as described. 90 95

4. The combination of an elevator and operating means therefor, of latches mounted on the landing and arranged to project into the elevator shaft and form a support for the platform, levers associated with said latches, rock shafts, strikers projecting from said rock shafts and arranged to engage and move said levers to retract the latches, and means for actuating said rock shafts from the elevator operating means, substantially as described. 100 105 110

5. The combination of an elevator and operating means therefor, of latches mounted in the landing arranged to project into the elevator shaft and form a support for the platform, levers associated with said latches, a pair of rock shafts journaled to either side of the elevator shaft, means for connecting said rock shafts to move together, connections for actuating said rock shafts from the elevator operating means, and connections 115 between said rock shafts and levers for engaging and moving the latter to retract the latches, substantially as described. 120 125

6. The combination of an elevator and operating means therefor, of latches mounted to reciprocate in the landing and arranged to project into the elevator shaft and form a support for the platform, spring means ar-

ranged to normally hold said latches in projected position, levers associated with said latches, a pair of rock shafts journaled to either side of the elevator shaft, means for connecting said rock shafts to move in unison, connections between one of said rock shafts and the elevator operating means, and strikers on said rock shaft adapted to

engage and move said levers to retract the latches, substantially as described. 10

In testimony whereof, I affix my signature, in presence of two witnesses.

JOHN M. HOWARTH.
